Application filed June 10, 1901. Serial No. 64,043. Term of patent 14 years.

To all whom it may concern:

Be it known that I, CHARLES A. BENNETT, a citizen of the United States, residing at Taunton, in the county of Bristol and State of Massachusetts, have invented and produced a new and original Design for the Handles of Spoons, Forks, or Similar Articles, of which the following is a specification, reference being had to the accompanying drawings, forming a part hereof, in which—

The minor features of the design are the finial *c* or end ornament of the handle *A*, the scrolls *d* on the sides of the aforesaid panel *b*, and the rib *e*, extending along the shank of the handle.

30

The obverse side of the handle *A* (shown in Fig. 2) is distinguished by scrolls *f* or leaves forming part of the lilies *a*, located at the outer end of the handle, and elongated and curved leaves *g*, bordering the panel *h* and also arranged at the junction of the handle-shank with the bowl *B* of the spoon.

35

It will be understood that my design is applicable to handles of knives and other articles analogous to spoons and forks.
